UNITED STATES PATENT OFFICE

VERNON E. CORNELL, OF CLEVELAND, OHIO, ASSIGNOR TO THE STEVENS METAL PRODUCTS COMPANY, OF NILES, OHIO, A CORPORATION OF OHIO

METALLIC RECEPTACLE AND CLOSURE THEREFOR

Application filed January 25, 1930. Serial No. 423,334.

My invention is an improvement in metallic receptacles or containers, and relates more particularly to closures for the same and to means for effecting a fluid tight seal between 5 the receptacle and the closure.

One of the objects of my invention is to enable metallic receptacles such as drums or barrels to be fitted with a full removable cover providing a tight fluid proof seal between 10 the cover and the receptacle, without the aid of tools.

Another object of my invention is to insure a fluid tight seal between the cover and the receptacle by uniformly distributing the 15 sealing pressure about the periphery of the cover and container.

A further object of the invention is to seal the cover in place against unauthorized removal.

20 Other objects and advantages of my invention will become more apparent from the following description of an embodiment thereof, reference being made to the accompanying drawing in which like reference 25 characters are employed to designate like parts throughout the same.

In the drawing—

Fig. 1 is a top plan view of an embodiment 30 of my invention, showing the cover on the receptacle in fluid tight sealed relation.

Fig. 2 is an enlarged fragmentary section taken on line 2—2 of Fig. 1.

Fig. 3 is a fragmentary plan view of the locking or clamping ring contracted to seal 35 the cover on the receptacle.

Fig. 4 is a view similar to Fig. 3 except that the ring is shown partly expanded as in removing the ring and cover from the receptacle.

40 Fig. 5 is an elevation of the locking or clamping ring looking in the direction of the arrows in Fig. 3.

My invention is particularly applicable to metallic containers or receptacles such as barrels or drums and the like, which are provided with a circumferential bead at their open ends for supporting a cover and for reinforcement purposes.

50 Referring to the drawing, in which I have illustrated an embodiment of my invention,

the barrel or drum is indicated at 1. The upper edge of the container is rolled to form a peripheral bead 2 at the open end thereof. A cover 3 comprising a cupped member having a peripheral upwardly and outwardly 55 extending flange 4, is supported by the bead 2 in such a manner that the cupped portion of the cover may be telescoped for a short distance within the container, as illustrated in Fig. 2. It will be noted that a portion of the flange 4 is slightly arcuate in cross section to conform with the approximate curvature of the upper surface of the bead, and that the outer edge of the flange terminates at a point 60 near that defined by the greatest outer diameter of the bead. Although I have shown the flange extending to a point equal to the greatest outer diameter of the bead, I find that the flange may extend to a point just short thereof, it being sufficient that the 65 flange extend completely over the packing 5 between the flange and the bead. The packing may consist of an annulus of any suitable packing material, and I have found that an annulus of flexible rubber tubing is very satisfactory for this purpose.

I have provided a simple means for removably securing the cover on the receptacle to effect a fluid tight seal between the same by exerting a substantially uniform pressure 70 on the cover and the bead in a direction substantially parallel to the axis of the container.

In the present embodiment this means includes a split contractible channeled ring 6 75 substantially U-shaped in cross section. The upper and lower flange and bead engaging walls respectively of the ring extend in substantially parallel planes only near their inner edges as shown in Fig. 2.

Thus it will be seen that upon contracting the ring the flange will be tightly pressed against the packing 5 and the supporting bead 2 under a substantially vertical pressure.

80 The contractible ring 6 comprises a pair of complementary sections each section being provided with inwardly extending lugs 7 and 8 near its ends. The lugs may be formed integrally with or separately of the ring sec- 85

tions and welded thereto in a plane lying in the upper inwardly extending side walls of the ring sections. Each of the lugs is apertured near its inner extremity.

- 5 In the illustration, I have shown levers 9 pivotally connected to the lugs 8 by means of pins 10 in the openings in these lugs. Links 11 are pivoted at one end to the lugs 7 by means of the pins 12 and at their other ends 10 to the levers 9 at 13. It will be noted that the points 13 lie between the ring sections and a line drawn through the respective points 10 and 12, when the levers are moved to contract the ring sections and seal the cover on 15 the container. In this manner accidental release of the levers from the locking position will be prevented. As the levers are moved to the position shown in Fig. 1 the ring sections will be drawn together laterally 20 to tightly press the cover against the packing and the bead.

When it is desired to seal the container against unauthorized opening, a tab 14 may be welded to the ring at a point where its 25 opening 15 will register with the openings in the levers 9 when the levers are swung toward the ring. The customary wire seal may be then inserted in the openings and sealed in the usual manner.

- 30 I have illustrated a means contemplated by this invention for exerting a lateral pressure between the ring and the side walls of the cover, to draw the ring inwardly and more easily contract the ring about the bead and 35 flange. This means includes arms 16 formed on each of the levers 9. The outer end of each of the arms is formed with a shoe 17, the outer or flange engaging wall of which is tapered slightly inwardly and forwardly 40 as shown more clearly in Figs. 3 and 4.

By inclining this wall relative movement between the shoe and the flange, upon swinging the levers 9, will be more easily accomplished. The arms 16 are of sufficient length 45 so that the shoes 17 will engage the flange under considerable lateral pressure and cause the ring sections 6 to be tightly contracted about the bead and flange when the levers 9 are moved to the position in Fig. 3, thereby 50 exerting and uniformly distributing the sealing pressure about the flange and the bead.

In Fig. 4 I have shown one of the levers 9 and the ring sections 6 in partly opened position to allow the shoe to release the lateral 55 pressure on the flange and ring. By further moving the levers to the right in Fig. 1, the ring sections may be expanded to a point where the circumference of the ring unit is greater than that of the flange or bead, to permit 60 its removal from the receptacle. In this manner the cover and packing ring may be lifted from the receptacle to permit cleaning or for emptying or filling the same.

It is to be understood that while I have 65 shown my invention applied to receptacles

having openings of the same diameter as the inner diameter of the receptacle, the invention is equally applicable to receptacles having restricted openings.

It will also be observed that by my invention the full removable cover may be clamped easily on the receptacle in fluid sealing contact and may be removed easily without the aid of tools.

In my copending applications Serial Numbers 423,333, 423,335 and 423,336 all filed on January 25, 1930, I have disclosed several other types of closures for metallic receptacles.

Various changes may be made in the details 80 of construction and arrangement of parts without departing from the spirit of the invention or the scope of the appended claims.

I claim—

1. The combination with a metallic receptacle having a bead rolled about its open end, and a removable cover for said receptacle having a marginal flange fitting over the bead, of a contractible channeled segmental clamping ring having walls engageable with the flange and the bead for pressing the same together when the ring is contracted, and means for contracting the ring including levers pivotally connected to the ends of one ring segment and links pivotally connected to 95 the ends of another ring segment, and to said respective levers.

2. The combination with a metallic receptacle having a bead rolled about its open end, and a removable cover for said receptacle having a marginal flange fitting over the bead, of a contractible channeled segmental clamping ring having walls engageable with the flange and the bead for pressing the same together when the ring is contracted, and means for contracting the ring including levers pivotally connected to the ends of one ring segment and links pivotally connected to the ends of another ring segment, and to said respective levers, and shoes carried by the said levers and engageable with the flange to exert a lateral pressure on the flange when the ring is contracted.

3. The combination with a metallic receptacle having a bead rolled about its open end, 115 and a removable cover for said receptacle having a marginal flange fitting over the bead, of a contractible channeled segmental clamping ring having walls engageable with the flange and the bead for pressing the same 120 together when the ring is contracted, and having lugs projecting inwardly of the ring, and means for contracting the ring including levers pivotally connecting certain of said lugs on one ring segment, and links pivotally 125 connected to certain other of said lugs on another ring segment and to said respective levers.

4. A clamping device for a metallic receptacle having a bead rolled about its open end 130

and a cover having a flange fitting over the bead, including a contractible, segmental, channeled clamping ring having walls engageable with the flange and the bead for pressing the same together when the ring is contracted, and means for contracting the ring including levers pivotally connected to the ends of one ring segment and links pivotally connected to the ends of another ring segment, and to said respective levers.

10 In testimony whereof, I hereunto affix my signature.
